(57) **CLAIM**

The design for combined cushion and mat, as shown and described.

DESCRIPTION

FIG. 1 is a front view of combined cushion and mat;

FIG. 2 is a top plan view thereof;

FIG. 3 is a rear side elevational view thereof;

FIG. 4 is a right side elevational view thereof;

FIG. 5 is a left side elevational view thereof;

FIG. 6 is a bottom plan view thereof; and,

FIG. 7 is a perspective view thereof.

In the drawings, the broken lines represent stitching forming part of the claimed design.
